US00D494436S1

(12) **United States Design Patent** (10) Patent No.: **US D494,436 S**
 Winig et al. (45) Date of Patent: **** Aug. 17, 2004**

(54) **TOOL HOLDER**(75) Inventors: **Alan Winig**, Wynnewood, PA (US);
Richard Winig, Villanova, PA (US);
James Eldon, Barto, PA (US)(73) Assignee: **Eye Designs LLC**, Collegeville, PA
 (US)(**) Term: **14 Years**(21) Appl. No.: **29/187,457**(22) Filed: **Aug. 1, 2003****Related U.S. Application Data**

(63) Continuation-in-part of application No. 29/175,165, filed on Jan. 30, 2003, now Pat. No. Des. 481,920.

Primary Examiner—James Gandy

Assistant Examiner—T. Chase Nelson

(74) Attorney, Agent, or Firm—Duane Morris LLP

(57) **CLAIM**

The ornamental design for a tool holder, as shown and described.

DESCRIPTION

FIG. 1 is a perspective view of the tool holder according to the invention;

FIG. 2 is a top view of the tool holder; and,

FIG. 3 is a bottom view of the tool holder.

The broken line showing of structure is for illustrative purposes only and forms no part of the claimed design.

1 Claim, 2 Drawing Sheets# US D494,436 S
